UNITED STATES PATENT OFFICE.

HENRY G. RUNNE, OF ROCHESTER, NEW YORK.

DESIGN FOR A DIRECTION INDICATOR FOR MOTOR VEHICLES.

Application filed December 3, 1927. Serial No. 24,374. Term of patent 14 years.

To all whom it may concern:

May it be known that I, HENRY G. RUNNE, a citizen of the United States, residing at Rochester, in the county of Monroe and State of New York, have invented a new, original, and ornamental Design for a Direction Indicator for Motor Vehicles, of which the following is a specification, reference being had to the accompanying drawing, forming part thereof.

In the drawing:

Fig. 1 is a face view of a direction indicator for motor vehicles showing my design,

Fig. 2 is a top view thereof disclosing my new design; and

Fig. 3 is an end view thereof disclosing my new design.

I claim:

The ornamental design for a direction indicator for motor vehicles, as shown.

HENRY G. RUNNE.
